EMERGENCY CIRCUIT CONTROLLER

Robert J. Parsons, Schenectady, N. Y., assignor to
 Consolidated Car-Heating Company, Inc., Albany, N. Y., a corporation of New York

Application May 9, 1934, Serial No. 724,715

6 Claims. (Cl. 200—168)

This invention relates to electricity, especially to circuit controllers, and more particularly to a form of circuit controller and enclosure therefor usable especially in an emergency.

5 Those familiar with the electrical art know that it is common to place circuit controllers in enclosed spaces where they may be reached only by the destruction of a frangible member. Such circuit controllers are intended, generally, for emergency use, that is, are only intended to be operated in an emergency or upon the occurrence of an unusual event. This fact is the reason why they are enclosed and protected by a frangible member which may be broken or destroyed in order to obtain access to the circuit controller itself.

It is commonly necessary to restore an emergency circuit controller, after being operated, to its normal inoperative condition before an opportunity is afforded to replace the frangible member. This causes a difficulty, in that the emergency circuit controller is not always properly conditioned upon the replacement of the frangible member.

25 A principal object of applicant's invention is to provide an emergency circuit controller, biased to one position, and enclosed in a space to which access may be had by destroying a frangible member, of such construction that the circuit controller is held normally out of its biased position by the action of the frangible member itself, and the circuit controller may be moved manually against its bias and held in such position by a further device which is automatically rendered ineffective by the replacement of the frangible member after its destruction.

Other objects and advantages will appear as the description of the particular physical embodiment selected to illustrate the invention progresses, and the novel features will be particularly pointed out in the appended claims.

In describing the invention in detail and the particular physical embodiment selected to illustrate the invention, reference will be had to the accompanying drawing and the several views thereon, in which like characters of reference designate like parts throughout the several views, and in which:

50 Figure 1 is a cross-sectional view of an enclosed emergency circuit controller embodying applicant's invention; Fig. 2 is a face view of the device as shown by Fig. 1, that is, as viewed from the left as shown in Fig. 1, with the front cover removed; Fig. 3 is a horizontal sectional view 55 of the device as shown by Fig. 1 on the plane as

indicated by the line III—III, viewed in the direction of the arrows at the ends of the line; Fig. 4 is a front elevational view of the enclosing case of applicant's invention.

Numerals 1 designate any suitable support to which an enclosing casing for an emergency circuit controller may be attached, such as a vertical wall. In this case applicant attaches his casing to the wall by means of attaching screws as 2.

Applicant's enclosing casing may be of any suitable or appropriate form just so long as it includes an opening in one of the walls closed by a frangible member, such as 3, properly positioned to cooperate with the circuit controller. In the particular form of enclosing casing shown, there 15 is a substantially hollow box 4 provided with a boss 5 on the top thereof for the reception of a wire conduit 6 through which wires or conductors 7 and 8 pass into the interior of the box or casing 4. 20

In the particular form of casing shown, applicant has made the entire front face 9 removable, it being attached to the base 4 of the box by means of screws as 10.

The front face 9 of the casing is provided with 25 an opening 11. This opening is closable by the frangible member 3. The frangible member 3 is held in place by screws, as 12, passing into the front face 9 of the casing. In order to place a frangible member 3 in place, it is necessary to remove the front face of the box, place the frangible member 3 in place, and then replace the front face of the box. 30

The frangible member 3 not only completely covers the opening 11 but also extends upwardly, 35 as best shown in Fig. 1, so that it forms a rest for the arm 13. This arm 13 is attached to the two arm lever 14 pivoted at 15 in the bracket 16 attached, as by screws 17, to an insulating body 18 which in turn is attached, as by screws 19, 40 to the back wall of the casing 4. The two arm lever 14 also carries the contact finger 20 which is positioned to cooperate at times with the contact terminal 21, attached to the insulating block 18 as by screws 22. 45

The circuit to be controlled by the emergency switch is a circuit formed through wire 7 which attaches to the wire clip 23 which is in turn fastened electrically and mechanically to the bracket 16, as by a screw 24, so that the circuit 50 is through the bracket to the pivot 15, the arm 14, the contact finger 20 and so to contact terminal 21 when contact finger 20 is in contact therewith, to wire clip 25 to which the wire 8 is attached. 55

With the parts as shown in Fig. 1, the arm 13 is supported by the frangible member 3 and so the contact finger 20 is out of contact with the contact terminal 21 and so the circuit through the wires 7 and 8 is broken. If frangible member 3 is destroyed, the spring 26 which acts as a normal bias to contact finger 20, will force finger 20 into contact with contact terminal 21 and close the circuit between wires 7 and 8.

After a frangible member 3 is broken, as by the hammer 27, and the circuit is formed between wires 7 and 8, it is often necessary before replacing a frangible member 3 to break the circuit, that is, restore the circuit condition to the normal open condition. This is done in applicant's device by reaching through the opening 11 with the hand or fingers and forcing arm 13 upwardly whereupon it is latched by latch 28 pivoted at 29 to a bracket 30 supported by the case 4, as by screws as 31. This latch 28 has a normal bias by reason of the spring 32 forcing it in the left hand direction, as shown in Fig. 1. When the frangible member 3 is broken and the arm 13 is raised, the latch 28 by means of latch face 33 reaches under the shoulder 34 of arm 13 when arm 13 has been pushed up sufficiently and so maintains arm 13 in the upper position with the contact finger 20 out of contact with the contact terminal 21.

If frangible member 3 could be replaced without unlatching arm 13, the device would be inoperative to perform its functions, that is, would be inoperative to close the intended circuit upon the breaking of the frangible member 3. In order to provide for this contingency, applicant provides a projection or horn 35 upon the latch 28 of such length and so positioned that it contacts with the frangible member 3, so that when the frangible member 3 is in place the latch 28 is pushed to the right as shown in Fig. 1 so as to unlatch arm 13 and cause it to be held by the top of frangible member 3.

From the hereinbefore described construction and mode of operation, it will be seen that applicant has provided a circuit controller for emergency use in an enclosed space, so arranged that the breaking of the frangible member which normally holds the circuit controller against a bias in normally open position will cause the circuit controller to be automatically closed, and that the circuit controller may be manually opened and maintained in the open position until such time as the frangible member is replaced whereupon the replacement of the frangible member will automatically release the circuit controller from its cooperation with the means which have been maintaining it in the normally open position so that it will then be in a position to function as before.

Although I have particularly described one particular physical embodiment of my invention and explained the operation, construction and principle thereof, nevertheless, I desire to have it understood that the form selected is merely illustrative, but does not exhaust the possible physical embodiments of the idea of means underlying my invention.

What I claim as new and desire to secure by Letters Patent of the United States, is:

1. In an emergency circuit controller, in combination: a biased circuit controller formed with an arm whereby the controller may be moved and held against its bias; walls forming an enclosed space, one of said walls provided with an opening; a frangible sheet covering said opening

and extending into the path of said arm whereby when the frangible sheet is in place the arm is held so as to hold the controller against its bias and whereby when the frangible sheet is destroyed the controller assumes the biased position; and a member adapted to be set manually to hold the controller against the bias, in the absence of a frangible sheet, said member being automatically rendered inoperative with relation to said controller upon replacement of a frangible sheet.

2. In an emergency circuit controller, in combination: a biased circuit controller formed with an arm whereby the controller may be moved and held against its bias; walls forming an enclosed space, one of said walls provided with an opening; a frangible sheet covering said opening and extending into the path of said arm whereby when the frangible sheet is in place the arm is held so as to hold the controller against its bias and whereby when the frangible sheet is destroyed the controller assumes the biased position; a biased pivoted latch provided with a latching face and positioned to swing to biased position when the arm is manually suitably moved, said latch provided with a projection normally resting against said frangible member and of a length such that the latching face is moved out of position to engage the arm.

3. In an emergency circuit controller, in combination: circuit terminals; means for bridging said circuit terminals, said means being normally open but biased to closed position; means including an arm and a frangible member for maintaining said first mentioned means open; a third means for maintaining said first mentioned means open; means cooperating with the frangible member whereby when the frangible member is replaced, after destruction, the third named means are positioned to free the first mentioned means.

4. In an emergency circuit controller, in combination: contact terminals; a member biased to bridge said terminals; a frangible member; means cooperating with the frangible member to maintain the first named member out of biased position; a second means for maintaining the first named member out of biased position; and means cooperating with the frangible member for preventing the second named means from acting.

5. In an emergency circuit controller, in combination: a biased circuit controller; walls forming an enclosed space within which said biased circuit controller is mounted, one of said walls having a removable part provided with an opening closed by a frangible sheet, and a means to controvert said bias and maintain said circuit controller in open-circuit position, said controverting means being adapted to be set in bias-controverting position either automatically, by the presence of said frangible sheet, or manually, at will, by an operator readily in the absence of said sheet, and while said removable wall part remains in place.

6. In an emergency circuit controller of the class described, in combination: an enclosure formed with an opening closed by a frangible means; a bell-crank-lever circuit-controlled mounted within said enclosure, having one arm provided with a contact maker and having its other arm extended into position to be engaged with said frangible means, contact terminals mounted in said enclosure in position to be bridged at times by said contact maker; a compression spring arranged to bias said bell-crank-lever into contact-making position to close the circuit, and

being effective in the absence of said frangible means; a swinging arm mounted in said enclosure and having a part adapted to be engaged normally with said frangible means and a latch portion adapted to be engaged with said other arm of said bell-crank, serving when in latching engagement to controvert said bias and maintain said lever in open circuit position; a spring to bias said latch arm against said frangible means

when the latter is present, and toward latching engagement with said other arm in the absence of said frangible means, said other arm of the bell-crank-circuit-controller being accessible through said opening, in the absence of said frangible means, for manual operation to its bias-controverting position.

ROBERT J. PARSONS.
